DIPPER BUCKET

Filed Nov. 4, 1929

Inventor:

Earl H. Fundom,
Bydstrup, Sev, Crittenden Co.,
Arkansas

UNITED STATES PATENT OFFICE

EARL H. FUNDOM, OF LIMA, OHIO, ASSIGNOR TO PETTIBONE MULLIKEN COMPANY, OF CHICAGO, ILLINOIS, A CORPORATION OF DELAWARE

DIPPER BUCKET

Application filed November 4, 1929. Serial No. 404,776.

My invention relates to dipper buckets such as are used for excavating, dredging, transferring loose material, or for other similar work.

5 My primary object is to provide a dipper bucket of such construction that the material to be transferred in the bucket may be scraped thereby into a position in which the loading of the bucket may be facilitated, or the material discharged from the bucket may be leveled by the bucket or shifted to a different location, as for example into a pile.

Referring to the accompanying drawings:

Figure 1 is a view in side elevation of a 15 portion of an excavator apparatus comprising a dipper bucket embodying my improvement.

Figure 2 is a bottom plan view of the bucket and a portion of the supporting structure therefor; and Figure 3, a broken enlarged section taken at the line 3 on Fig. 1 and viewed in the direction of the arrow.

20 My invention generally stated consists in providing on the dipper bucket at its bottom and preferably at the lower edge of its front portion, a scraping device, in the form of a lip, which extends into a position in which it may engage with, and scrape to the desired position, material to be transferred 25 in the bucket or the material after it has been transferred in the bucket.

In the particular illustrated embodiment 30 of my invention, the dipper shown and represented generally at 4 comprises a front section 5 shown as equipped at its upper edge with dipper teeth 6, a back portion 7, and side portions 8.

In this embodiment of the invention the scraper above referred to is in the form of a 35 lip 9 located at the lower edge of the front 40 5 and integrally formed therewith, though it is not necessary that it be so formed, the lip shown having its end walls downwardly convergent as represented at 10.

45 The lip 9 extends in front of the opening in the bottom of the bucket, this opening being provided with any suitable removable closure, as for example a sliding door such as that represented at 11. The door 11 extends at its opposite lateral edges into in-

wardly opening channels 12 defined by the lower edges of certain portions of the side walls of the bucket and the inwardly extending lugs 13 provided on certain of the other members forming the side wall structure of the bucket, the side wall structure of the bucket being provided with rearwardly projecting extensions 14 presenting guide lugs 15 in which the door, at its edges, is slidable.

55 The bucket is shown as connected with the outer end of a dipper stick 16 in accordance with common practice, this stick being associated with a boom 17 as commonly provided in apparatus of this general character.

The door 11 is shown as connected at a 60 clevis 18 with a cable 19 extending over a pulley 20 on the boom 17 for operation in any suitable way, as for example by a windlass (not shown), to control the position of the door 11.

65 It will be understood from the foregoing that by moving the bucket along the material to be transferred therein with its scraper lip 9 engaging the material, the material may be drawn into a pile or otherwise suitably displaced for facilitating the loading of the bucket and the material discharged from the bucket may be either leveled or moved into the desired position, as for example into a pile, by drawing the bucket along the material with the scraper lip 9 extending into the material.

70 The structure thus provided, therefore, affords the dual adaptability of transferring material therein and also the shifting or 75 moving of the material either before or after its transference in the bucket.

79 While I have illustrated and described a particular construction embodying my invention, I do not wish to be understood as 80 intending to limit it thereto as the same may be variously modified and altered without departing from the spirit of my invention.

85 What I claim as new, and desire to secure by Letters Patent, is:

90 1. A dipper bucket having a digging portion at its upper edge and provided at its lower portion with a scraper element extending below the bottom of the bucket, for the purpose set forth.

2. A dipper bucket having a digging portion at its upper edge and provided at the lower edge of its front portion with a scraper element extending below the bottom of the bucket, for the purpose set forth.
3. A dipper bucket having a digging portion at its upper edge and provided at the lower edge of its front portion with a lip depending below the bottom of the bucket and forming a scraper element, for the purpose set forth.
4. A dipper bucket having a digging portion at its upper edge and provided at its lower portion with a lip extending below the bottom of the bucket and forming a scraper element with its end portions downwardly converging.

EARL H. FUNDOM.
